UNITED STATES PATENT OFFICE.

THOMAS OLINGER, OF HOLLAND, MICHIGAN, ASSIGNOR TO FEDERAL MANUFACTURING COMPANY, OF HOLLAND, MICHIGAN, A CORPORATION OF MICHIGAN.

FURNACE-FLUE CLEANER.

Application filed September 8, 1925. Serial No. 54,879.

This invention relates to a flue cleaner for furnaces. In furnaces of many makes, a radiator is located at the upper end of the fire pot and combustion chamber, through which the hot products of combustion pass on their way to the chimney. This radiator is annular in form and substantially circular in cross section. The products of combustion in their passage through the radiator deposit soot, 5 ashes and the like, and it is desirable at times to remove such deposits in order that the radiator may be heated more fully and deliver heat to the air which passes to the rooms which the furnace is to heat. The radiator, 10 at one side at least, is provided with a clean-out opening through which the deposits therein may be removed.

It is a primary object and purpose of the present invention to provide an exceptionally simple, yet effective, cleaner for the radiator flue of a furnace, and one which will automatically turn to an ineffective position as it is moved into the flue away from the clean-out opening through which it is inserted, thereby passing over the deposits in the flue, but which, when the cleaner is moved in the opposite direction, will immediately and automatically assume its effective operating position, engaging with and scraping the deposits from the flue and carry the same ahead of it to the said clean-out opening. The flue cleaner is made of two parts only, 25 and can be manufactured at very low cost.

The accompanying drawing and the following description outline the preferred embodiment of the invention, in which drawing,

Fig. 1 is a perspective view of the flue cleaner made in accordance with my invention.

Fig. 2 is a fragmentary perspective view of the wire or rod element of the flue cleaner construction.

Fig. 3 is a fragmentary section through the disk of the flue cleaner, the handle member being shown in side elevation, and the parts disposed in operative position, and

Fig. 4 is a view similar to that shown in Fig. 3, with the parts in partially collapsed and ineffective position.

Like reference characters refer to like parts in the different figures of the drawing.

In the construction of the flue cleaner, a circular disk 1 of sheet metal is used, the 55 diameter of the same being smaller than the

inner diameter of the furnace flue of the radiator. This disk, toward one side has a bead 2 pressed therefrom, the metal of the disk at each end of the bead being pressed in the opposite direction for a short distance, as indicated at 3. This disk is readily blanked and formed by means of suitable dies on a punch press, as is evident.

The handle member used with the disk, 60 comprises a heavy wire or wire rod 4 of the required length, at least somewhat longer than half the length of the radiator flue. At its outer end said wire is fashioned into a handle 5. The opposite end portion is designed to be attached to the disk, and at a 65 distance from its end, the wire is bent outwardly at an obtuse angle to the principal length of the wire, making an angularly disposed section 6, and is then bent back to make the pintle section 7 disposed at right angles to the length of the part 4 so that it can pass under the bead 2 of the disk. After it has been passed under said bead, the terminal portion is bent so as to lie in a plane substantially at right angles to the plane in which the wire 4 and its sections 7 and 6 lie.

This completes the flue cleaner. It is evident that the disk is pivotally mounted on the pintle section 7 and may swing thereon through an angle of ninety degrees. In one position, that shown in Fig. 3, the disk is at one extreme, at right angles to the length of the wire, being stopped from further movement beyond such position by the stop section 8. The disk may be swung in the opposite direction until stopped by its engagement with the wire 4 and section 6 thereof, and Fig. 4 shows an intermediate position of the disk between its two extreme positions.

The wire rod 4 is of spring material, or at 90 least of a material which tends to return to its original position after being sprung therefrom, so that it will readily follow the curve of the radiator flue. The disk is inserted at the clean-out opening of the radiator and moved inwardly therein. During such movement, the disk will turn from the position shown in Fig. 3 to a position approximately like that shown in Fig. 4, passing freely over the deposits in the flue. On withdrawal of the flue cleaner, the edge of the disk, engaging with the deposit, causes the disk to automatically turn to its right angle position with reference to wire 4, the edge of the disk engaging with and scraping 95 100 105 110

the deposits from the inner sides of the flue. The disk cannot turn farther after it has come into engagement with the stop section 8. Accordingly, the deposits in the flue are scraped from the flue and pushed ahead of the disk until delivered from the flue through the clean-out opening. It is desirable to have the disk 1 formed dish shape as shown with the concave side forward toward the handle. When it is so formed it will more effectively carry the flue deposits ahead of it.

The flue is cleaned in both directions from the clean-out opening and with the flue cleaner described, all of the deposits on the inside of the flue may be scraped and removed from the inner walls thereof. This flue cleaner is particularly simple in construction. It comprises but two parts, both of which are exceptionally simple and easy to make. The assembly is easy also. The flue cleaner is very effective in operation. The

invention is defined in the claim appended hereto, and is to be considered as comprehensive of all forms of structure coming within their scope.

25

I claim:

In a flue cleaner, a plate of sheet metal formed at one side of its center with an outwardly pressed bead open at both ends, an elongated wire handle member formed at one end with a pintle section extending transversely to the length of the handle, said pintle member extending through said bead for pivotal connection of the plate to the handle, said pintle section terminating in a stop section turned at right angles thereto, said stop section serving to retain the pintle within the bead and to engage the plate to limit its pivotal movement in one direction.

30

In testimony whereof I affix my signature.
